UNITED STATES PATENT OFFICE

2,657,418

VACUUM CLEANER BRUSH MOUNTING

Frank S. Howard, Chicago, Ill., assignor to Birtman Electric Company, a corporation of Illinois

Application November 9, 1946, Serial No. 708,993

2 Claims. (Cl. 15—392)

1

This invention relates to a vacuum cleaner, and particularly to a brush mounting for a vacuum cleaner.

Vacuum cleaners of the rotatable brush type employ a nozzle with a work-contacting opening through which dirt-laden air is drawn, and a rotating brush to loosen dirt from the work being cleaned. The brush employs end bearings which are ordinarily mounted on the end walls of the nozzle, and are usually protected from the dirt in the air stream. Various types of bearings and mounting devices have been used in the past on these brushes, but not all have been completely successful, as some were bulky and expensive, and sometimes they did not maintain the brush in the exact alignment necessary.

In this invention the brush mounting is very simple in operation, and is quite cheap to build. The brush may be readily removed from the nozzle, and it is held in perfect alignment during the operation of the vacuum cleaner. The invention broadly comprises a rotatable brush in a nozzle and having an end bearing member, a co-operating bearing member engaging the first bearing member, a socket in the end wall of the nozzle for receiving the bearing members, an opening on the bottom of the socket through which the bearing members may be inserted and removed, and a removable closure for the opening adapted to complete the socket. In a preferred embodiment the socket-contacting portions of the co-operating bearing member are made of a resilient material such as rubber or synthetic rubber.

The invention will be described as related to the embodiment set out in the accompanying drawings. Of the drawings, Fig. 1 is a side elevation of a vacuum cleaner embodying the invention; Fig. 2 is a bottom view of the cleaner; Fig. 3 is a view similar to Fig. 2 showing the bottom plate of the cleaner removed to expose the bearings and with portions broken away for clarity of illustration; Fig. 4 is a plan view of the bottom plate of the cleaner; Fig. 5 is a front end view of said plate; Fig. 6 is a side view of said plate; Fig. 7 is a vertical section taken along line 7—7 of Fig. 2; and Fig. 8 is an enlarged fragmentary sectional view through the end of the cleaner brush and its mounting.

The vacuum cleaner shown in the accompanying drawings comprises a casing 10, a nozzle 11 at the front thereof, a handle 12, a dust separating bag 13, front wheels 14, intermediate wheels 15, rear wheels 16 normally positioned above the floor, a fan chamber 17, a rotatable fan 18 therein, a

2

rotatable brush 19 in the nozzle 11, a belt 20 extending from the brush to a belt driving shaft 21 concentric with the fan 18 and used for driving the fan, an air inlet opening 22 at the bottom of the nozzle 11, an air inlet opening 23 to the fan chamber 17, an air passageway 24 extending from the nozzle to the fan chamber opening 23, and a belt guard 25 for separating the belt 20 from the air in the passageway 24. The dirt-laden air is exhausted from the fan chamber 17 through an exhaust passageway 26 into the bag 13.

The rotatable brush 19 is provided with removable brush elements 27 having bristles 28 thereon. These brush elements are adjustable by means of bolts 29 to compensate for wear on the bristles. Compression springs serve to urge the brush elements outwardly. This construction of the brush is described and claimed in the Charles H. Sparklin and Frank S. Howard copending application Serial No. 663,710, filed April 20, 1946, now Patent No. 2,568,772, issued September 25, 1951.

The brush 19 has a cylindrical body portion 30 forming the brush spindle and is provided at each end with a cap 31 having an outwardly extending cylindrical rim 32. This rim fits closely within the end of the body portion 30 and is attached thereto. In the center of the cap 31 there is provided an outwardly extending pin 34 riveted on the cap and arranged in axial alignment with the cylindrical body portion 30 of the brush 19.

The pin 34 is adapted to receive a bearing member 35. This bearing member 35 comprises a cup shaped member 36 having an inner end 37 of larger diameter than the outer end 38. Within the outer end 38 there is located a cylindrical bearing 39 of substantially the same length as the cup 36 adapted to receive the pin 34. Between the inner end 37 of the cup 36 and the cylindrical bearing 39 there is located a felt washer 70. Attached to the outer end 38 of the cup 36 is a block 40 of resilient material such as natural or synthetic rubber having a square cross-section. This block covers the sides of the outer end 38 and covers the end thereof except for the small hole 71. A thrust plug 72 is provided within the cup 36 at the end of the cylindrical bearing 39 and against which the pin 34 bears when the bearing member 35 is in place. The bearing member 35 is readily inserted on and removed from the pin 34 when the brush is free from the cleaner. As the bearing 39 is cylindrical and is fitted within the cup 36 and the resilient material 40 is relatively square with both being axially aligned, the

resilient material has thin portions in the plane shown in Figure 8 and relatively thick portions diagonally therethrough as shown in Figure 7. These thin portions are aligned with the pull of the belt so as to prevent excessive yielding while the thick portions are diagonal to the belt so as to absorb vibration. Thus, the structure produces maximum vibration absorbing with minimum yielding.

The bearing member 35 which includes the resilient block 40 is designed to be tightly held within a socket 41 formed integrally with the end wall 42 of the nozzle 11. This socket 41 comprises parallel substantially vertical walls 43 having an open bottom 44 through which the resilient block 40 may be inserted. The block fits within the recess 45 formed by the inner surfaces of the walls 43 and the flat surface 46 extending between the tops of the walls 43. This construction is shown most clearly in Fig. 7.

In order to hold the bearing 35 within the socket 41 there is provided an upwardly extending closure member 47 having a flat top portion 48 arranged to bear against the bottom of the resilient block 40. The closure member 47, as shown, is part of a work-contacting end portion 49 of the nozzle opening 22. The end portion 49 is formed integrally with the rear work-contacting portion 50 of the nozzle opening 22, which in turn is formed integrally with the removable bottom plate 51 forming the bottom of the air passageway 24. This bottom plate 51 when in place forms the bottom of the air passageway 24 and the bottom of the belt guard 25, and has an extended front portion 52 passing under the brush beneath the belt. The extended portion has upwardly extending members 53 on either side of the belt to protect the brush contacting portion of the belt from dust. The bottom plate is also provided with a spring-actuated rear gate 54 through which a converter attachment may be inserted and a raised portion 55 for holding the converter attachment against the air inlet 23 to the fan chamber 17. The bottom plate 51 is described and claimed in my copending application Serial No. 708,157, filed November 6, 1946.

Because of the resiliency of the block 40, it is held tightly within the socket 41. This is provided for by preferably making the block slightly larger than the socket. The block also serves to absorb vibration and shock set up in the brush 19. As can be seen, the brush may be easily removed from the cleaner by removing the bottom plate 51 and pulling the brush, together with its end bearing members 35, from their sockets. The brush can be just as easily reinserted by forcing the blocks 40 into the socket.

Around the front of the nozzle 11 there is located a furniture guard 56 engaging projections 57 on the front of the nozzle that prevent upward or downward displacement of the guard. The ends of the furniture guard are releasably held by means of holding member 58. The furniture guard is described and claimed in my copending application Serial No. 708,482, filed November 8, 1946.

In order to protect the bearings 35 from dust in the dust-laden air stream there are provided upward projections 60 formed integrally with the bottom plate 51, side members 49 and rear member 50. Each projection 60 is spaced inwardly from a closure member 48 and has a curved top surface 61 to closely embrace the spindle of the brush 19.

Having described my invention as related to

the embodiment shown in the accompanying drawings, it is my intention that the invention be unlimited by any of the details of description unless otherwise specified, but rather be construed broadly within its spirit and scope as set out in the accompanying claims.

I claim:

1. In a vacuum cleaner including a nozzle, a removable base plate on the cleaner, a rotatable brush in said nozzle including a spindle, a driving belt engaging said spindle, an extended pin member on the end of the spindle aligned axially therewith, a removable bearing having a cylindrical part embracing the pin member and a vibration-absorbing resilient material of substantially square cross-section attached to the outer surface of the cylindrical part, a substantially rigid socket in the nozzle rigid therewith and shaped similarly to the bearing to prevent rotation of the bearing in the socket and having an open bottom through which the bearing may be inserted and removed, said socket tightly receiving the bearing with the resilient material being under compression, and a closure on the removable base plate extending substantially completely across said open bottom to complete the socket and pressing tightly against substantially the entire corresponding side of said resilient material, said resilient material of the removable bearing having thick portions extending diagonally of the square cross section of the bearing and thin portions intermediate the thick portions, said thin portions of the square resilient material being substantially aligned with the driving belt to prevent excessive yielding of the resilient material under the pull of the belt and said thick portions being arranged diagonally to the belt to absorb vibration.

2. In a vacuum cleaner including a nozzle, a rotatable brush in the nozzle having end bearing members on the ends of the brush axially aligned therewith, each end bearing member comprising a cylindrical metal part and a block of vibration-absorbing resilient material of substantially square cross-section attached to the outer surface of the cylindrical part, a rigid socket at each end of the nozzle and rigid therewith receiving one of the blocks of resilient material, each socket being shaped similarly to its block and tightly enclosing the block, the resilient material of each bearing member having thick portions extending diagonally of the square cross section of the bearing member and thin portions intermediate the thick portions and means removably retaining the bearing members in their sockets, said thin portions of resilient material being substantially aligned with the driving belt to prevent excessive yielding of the resilient material under the pull of said belt and the thick portions being arranged substantially diagonally to the belt to aid in absorbing vibration.

FRANK S. HOWARD.
